CLAIM

The ornamental design for a combined bottle and stopper, as shown and described.

DESCRIPTION

FIG. 1 is a front elevational view of a combined bottle and stopper showing my new design, the rear elevational view being identical;

FIG. 2 is a right, end elevational view thereof, the view from the left being identical;

FIG. 3 is a top plan view thereof;

FIG. 4 is a bottom plan view thereof;

FIG. 5 is a perspective view thereof;

FIG. 6 is a front elevational view of the combined bottle and stopper shown in an exploded condition;

FIG. 7 is a right end elevational view of FIG. 6;

FIG. 8 is a top plan view of the bottle shown without the stopper for clarity of illustration; and,

FIG. 9 is a perspective view of the combined bottle and stopper shown in an exploded condition.
